[57] CLAIM

The ornamental design for a power strip housing, as shown and described.

DESCRIPTION

FIG. 1 is a perspective view of a power strip housing in accordance with our new design;

FIG. 2 is a top plan view thereof;

FIG. 3 is a bottom view thereof;

FIG. 4 is a right side elevational view thereof, the left side elevational view being a mirror image of the right view shown;

FIG. 5 is a front elevational view thereof; and,

FIG. 6 is a rear elevational view thereof.

The broken lines showing further details of the power strip housing are for illustrative purposes only and form no part of the claimed design.
